SEESAW

Thomas Serpico, Brooklyn, N. Y.

Application June 25, 1932. Serial No. 620,633

6 Claims. (Cl. 208—34)

This invention relates more particularly to that type of seesaw device which has a traveling movement imparted thereto by the seesawing operation, although some of the features of improvement may also be embodied in other kinds of seesaw devices.

Among the objects of the invention is to provide a traveling seesaw device which will afford a maximum of pleasure and amusement to the 10 riders, which will be convenient and easy to operate, and which will operate effectively and reliably.

Another object is to attain simplicity of construction together with economy and convenience 15 in manufacture as well as adequate strength and durability. Other objects and advantages of the invention will hereinafter appear.

In carrying out the invention there is provided an improved arrangement of supporting 20 wheels by means of which the device is propelled and steered, improved power-transmitting operation mechanism through which traction is affected, an improved steering gear, an adjustable spring counterbalance and an improved adjustable seat back construction in cooperation with 25 adjustable hand holds. The invention also further includes various features of construction and combinations of parts, as will appear from the following description.

One embodiment of the invention, shown in the 30 accompanying drawings, will now be particularly described and thereafter the invention will be pointed out in claims, reference now being had to the drawings, in which:

Figure 1 is a plan view of a traveling seesaw device in which the invention is embodied;

Figure 2 is a vertical longitudinal section of such device taken substantially on the zig-zag line 2—2 of Figure 1;

Figure 3 is a horizontal section on the line 3—3 of Figure 2; and

Figure 4 is a rear end elevation as viewed from the left in the preceding figures.

The particular traveling seesaw device shown in the drawings as an embodiment of the invention is indicated as being constructed largely of metal, but with some parts of wood, although the relative proportions of these materials may be varied as desired under any particular circumstances. However, metal parts in such a device are inexpensive and commonly more durable than wood.

The illustrated device has a main frame plate 1 of suitably strong and thick metal such as steel. This frame plate is symmetrically shaped, as ap-

pears most clearly in Figure 3, to provide narrower front and rear end extensions, with shoulders at the opposite sides of these respective extensions, all corners being rounded. The frame as a whole further includes a transversely arranged riser or upright 2 which rises from the frame plate 1 midway of its length. This upright is in general of inverted U-shape to provide a bench, as appears most clearly in Figure 4. The lower ends of the legs or standards of this U-shaped bench are rigidly and firmly secured to the frame plate 1 adjacent to its edges by means of, for example, screws or bolts (not shown). This upright 2 is indicated in the drawings as made from wood but it could be of metal, substantially of the shape shown or of a more or less different shape.

The entire device is supported for traveling movement upon four rubber-tired disc wheels 3, 4, 5, and 6, comprising the two larger left and right side wheels 3 and 4, and the two smaller front and rear wheels 5 and 6. The left hand side wheel 3 is a traction wheel, fixed on the end portion of a drive shaft 7 journaled in a pair of bearings 8, 8 secured on the lower side of the platform formed by the frame plate 1. The other or right hand side wheel 4 is merely a supporting wheel, being an idler loosely rotatively mounted on the other end portion of the drive shaft 7. The drive shaft 7 is located midway of the length of the frame platform 1 in vertical alignment with the upright 2, with the side wheels 3 and 4 beyond the edges of this platform, while the smaller front and rear wheels 4 and 5 are entirely below the level of this platform at its front and rear ends.

The front wheel 5 is a steering wheel, while the rear wheel 6 is a caster wheel. The steering wheel 5 has an axle 9 carried by a steering fork 10. This steering fork has its vertical stem at the top thereof swiveled in a bearing through the front end of the platform frame plate 1. The upper end of this stem has a disc 11 fixed thereon just above the frame plate 1. This disc is held in place and also the stem of the steering fork 10 is retained in its bearing in the plate 1 by means of a control screw 12. The steering fork 10 may be turned for steering by means of the disc 11, as will hereinafter appear. The caster wheel 6 has an axle 13 carried by a caster fork or bracket frame 14 the caster stem of which passes through and is journaled in a bearing in the rear end of the frame plate 1. The stem of the caster fork 14 is retained in its bearing by a washer 15 above

the frame plate 1 and held in place by a control screw 16.

An elongated seesaw member 17 extends longitudinally or fore and aft in elevated position 5 above the frame plate 1 beyond which it projects at both ends and is fulcrumed at the middle of its length on the top of the cross bar which joins together the legs or standards of the bench or upright 2. This seesaw member may be desirably 10 formed of a suitably strong spring steel plate, as indicated in the drawings. At the middle of its length the seesaw plate 17 is of a width substantially equal to the length of the fulcrum bench 2, thereby providing sufficient stiffness and strength. 15 This seesaw plate more or less gradually decreases in width towards its ends, terminating in suitably narrow seat-forming end portions having parallel lateral edges. For effectively serving its practical purpose as well as for ornamental effect this seesaw plate may have substantially the contour shown in Figure 1. This seesaw plate will be resiliently yieldable to a desirable slight extent under the weight of the riders.

The seesaw member 17 is fulcrumed to rock on 20 the upright 2 by means of a stiff transverse rod or shaft 18 which is shown as firmly secured to the seesaw plate 17 against its lower side by a pair of screws 19, 19. This shaft 18 rests and may rock in an arcuate groove along the top of the upright 2 which is beveled to incline downward 25 away from this groove to provide clearance for the seesaw member 17 in its rocking movement. The seesaw member 17 is further pivoted and held in place by means of reduced journal ends 30, 20 on the shaft 18 which are pivoted in bearings 21, 21 secured by screws 22, 22 to the upright 2.

The operating mechanism comprises power-transmitting connections for imparting rotation 40 to the traction wheel 3 from the rocking seesaw member 17. In the embodiment of the invention illustrated in the drawings, this operating mechanism includes gearing which is shown as multiplying gearing, although so far as the invention 45 is concerned the gear ratio might be different and could, for example, be reducing gearing. In the construction shown in the drawings, a small first spur gear 23 is fixed on the drive shaft 7 between its bearings 8 and at the center of the platform 50 plate 1 above which this gear slightly projects through an opening provided for the purpose.

A second and larger spur gear 24, shown as twice the diameter of the smaller gear 23, has 55 intermeshing driving engagement with the latter. This driving gear 24 is fixed upon a crank shaft 25 which is located directly above the drive shaft 7. The crank shaft passes through and is journaled in a pair of side plates 26, 26 between which the driving gear is rotatably held which also prevents longitudinal movement of the crank shaft. These plates 26, 26 form parts of a gearing frame which at its lower end is firmly and rigidly secured to the platform frame plate 1 and which at its upper end is notched to have interlocking 60 engagement with the cross bar of the upright 2, so that there is thereby a mutual bracing effect, particularly of the upright 2, longitudinally of the platform 1.

A pair of similar crank arms 27 and 28, of equal length, are fixed respectively upon the opposite projecting ends of the crank shaft 25. In the construction shown either one or the other of these crank arms may be operatively utilized 70 in the driving connection while the other crank arm necessarily rotates idly, as will presently appear.

As illustrated in the drawings, the adjustments are such that the left hand crank arm 27 is utilized as an operating crank while the right hand crank arm 28 is an idler.

The left hand crank arm 27 is connected to 80 the seesaw plate member 17 to be operated thereby by means of a two-part longitudinally telescopic connecting rod. This connecting rod comprises a lower part 29 in the form of a sleeve and an upper rod part 30 telescoped into the sleeve and locked in longitudinally adjusted condition there-in by means of a set screw 31 in the sleeve part 29 to clamp the rod apart 30. The lower end of the sleeve part 29 is pivoted on the wrist pin of the crank 27 on which it is held in place by an end screw 32 together with a washer 33. The upper end of the rod part 30 is pivotally connected to the seesaw plate member 17 in rearwardly spaced relation from its fulcrum rod 18 by means of a pivot pin 34 carried by a depending bifurcated bracket 35 secured by bolts 36, 36 to the screw member.

The pivot pin 34 is shown as spaced from the fulcrum shaft 18 a distance which is substantially three times as great as the effective length of 100 the crank 27. It is clear that this operatively connected connecting rod may be adjustably lengthened or shortened thereby adjusting the position of the seesaw member 17 in its rocking movement. It is of course to be understood from the drawings that the clamping screw 31 is in tightened condition so that thereby the two telescopic parts 29 and 30 of the connecting rod are securely locked together to operate as a unit and by reason of which the crank 27 is operatively connected to the seesaw member 17.

It is to be understood from the drawings that the other or right hand crank arm 28 has an idling pivotal connection to the seesaw member 17 by means of a longitudinally telescopic connecting rod which is of the same construction as that just described for the left hand crank arm 27. This connecting rod for the right hand crank 28 similarly comprises a lower sleeve part 37 in which an upper rod part 38 freely telescopes, the sleeve part 37 being provided with a set screw 39 which in this instance is left in loose or unclamping relation with the telescoping rod part 38 so that thereby the latter is free to slide in the sleeve 37.

The lower end of the sleeve part 37 is pivoted on the wrist pin of the crank 28 and held thereon by a screw 40 and washer 41. The upper end of the rod part 38 is pivotally connected to the seesaw member 17 in forwardly spaced relation from its fulcrum rod 18 by means of a pivot pin 42 carried by a depending bifurcated bracket 43 secured by bolts 44, 44 to the seesaw member. The spacing of the pivot pin 42 from the fulcrum rod 18 is substantially equal to three times the effective length of the crank 28.

The free telescopic sliding movement of the two parts 37 and 38 of the idling connecting rod is clearly indicated in Figure 2, in which this connecting rod is shown as elongated or drawn out substantially to the greatest extent, in which it is of considerably greater length than the operating connecting rod, the two parts 29 and 30 of which are locked together. In another position 140 in the cycle of movement, substantially opposite to that shown, the freely telescopically sliding parts 37 and 38 of the idling connecting rod will be pushed together substantially to their greatest extent so that this connecting rod will thus be 150

shorter than the operating connecting rod with its parts 29 and 30 locked together.

The right hand connecting rod may be used as the driver instead of the left hand connecting rod, merely by loosening the locking screw 31 of the latter and tightening the locking screw 39 of the former with its parts 37 and 38 in operatively correct adjusted position. With both of the locking screws 31 and 39 set tight the entire mechanism would be locked against operation, as is evident from Figure 2. The above described operating mechanism not only provides for substitute operation by means of either one or the other of the cranks 27 or 28 but also desirably results in a balanced appearance of the entire seesaw device as a whole.

It will now be clearly evident that one of the connections may be made so as at all times to be rigid or non-telescopic, with the other connection then made to be at all times freely telescopically slideable as an idler. For example, with the left hand connecting rod for the crank 27 made all in one piece or otherwise permanently non-slideable, the right hand connecting rod would be made to be permanently freely telescopically slideable, the clamp screw 39 then being omitted. In such case the operation would be the same as above described and indicated in the drawings, i.e., with the left hand locking screw 31 tightened and the right-hand locking screw 39 loosened.

The steering is done by the rear seat rider, since this rider faces forward. In carrying out this feature, the steering gear connections include a pair of co-operating oppositely movable flexible connecting members extending fore and aft. A pair of steering chains 45, 45 have their adjacent front ends connected respectively to eyes 46, 46 on the disc 11 of the steering fork 10 at equally distant opposite sides laterally from the pivotal axis of the steering fork and its disc 11, which thus becomes a two-armed steering lever. These chains extend rearwardly alongside of each other in spaced relation and have their rear ends respectively connected to lateral eyes 47, 47 carried on the upper side of and equidistantly spaced from the pivotal axis of a steering disc 48, which is immediately above the rear of the wider central portion of the frame plate 1, and which forms a two-armed operating lever for causing the chains 45 to be moved concomitantly in opposite directions for thereby pivotally rocking the steering wheel 10 in its steering operation.

It will be noted that the steering fork 10 will be rocked in the same direction as the steering disc 48 and to a somewhat greater extent by reason of the slightly longer lever arms on the steering disc 48 than on the steering fork disc 11, thereby requiring a small amount of slack in the connecting operating chains 45, 45. Two pairs of guide eyes 49, 49 are desirably provided on the platform plate 1 for these chains, one such pair being located in forward adjacency to the steering disc 48 and the other pair being intermediate located relatively to the steering fork disc 11. These pairs of guide eyes 49, 49 are shown as mounted upon the respective ends of a reinforcing strip 50 which forms also a base plate for the lower ends of the gear frame plates 26, 26.

The steering disc 48 is fixed on the lower end portion of the lower section 51 of an upright telescopic steering shaft. Below the steering disc 48 this shaft section 51 is pivoted in a bearing 52 which is fixed to and projects below the frame plate 1, this shaft section being retained in its bearing by a pin 53 through the end of the shaft

below the bearing. The upstanding major portion of this shaft section 51, above the disc 48, is tubular and has a longitudinal slot 54 extending diametrically through it, this tubular slotted portion terminating at the top in an annular cap 55, at about two-thirds of the distance upwardly from the frame plate 1 to the level of the seesaw member 17 (Figures 1 and 4).

The upper section 56 of the telescopic steering shaft telescopes downward into the lower tubular section 51 for free longitudinal sliding movement therein. These two shaft sections 51 and 56 are coupled together to rotate as a unit at all times irrespective of their relative sliding telescopic movement, by means of a cross pin 57 fixed in the lower end of the upper section 56 and projecting through the slot 54 at both sides of the lower section 51 (Figures 1 and 4). The upper shaft section 56 projects above the seesaw member 17 through a longitudinal slot 58 in the latter, which provides for the arcuate movement of the rocking seesaw member. This upper shaft section 56 is carried by the seesaw member 17 to move up and down therewith, by means of a collar 59 fixed against upward movement on the upper shaft section 56 above the seesaw member and conically tapered on its lower side for smooth sliding and angular engagement with the edges of the slot 58 in the seesaw member. The upper steering shaft section 56 is thus carried by the seesaw member 17 at a location thereon conveniently forward from its narrower seat-forming portion at the rear end thereof.

At a convenient distance above its supporting collar 59 the shaft section 56 terminates in a steering head 60. A combined hand hold and steering handle 61 has a forwardly projecting horizontal T-stem 62 passing through the steering head 60 and adjustably held therein by a thumb screw 63, the stem 62 desirably having a flat thereon to be engaged by the screw. It will be obvious that the hand hold provided by the steering handle 61 will rise and fall with the rear end portion of the seesaw member 17 and will be maintained in substantially uniform spaced relation above this seesaw member, relatively to the fulcrum of which it may be adjusted.

Another hand hold 64 is provided conveniently rearward from the front seat-forming portion of the seesaw member 17 by which this front hand hold is carried. This hand hold 64 has a rearwardly projecting T-stem 65 which passes through a supporting head 66 in which it is adjustably held by a thumb screw 67 which may desirably engage with a flat on the upper side of the T-stem. The head 66 is rigidly fixed on the upper end of an upstanding stem 68 the lower end of which is firmly and rigidly secured to the seesaw member 17, so that thereby the hand hold 64 is conveniently spaced above the seesaw member and mounted for forward and back adjustment relatively thereto.

Similar seatbacks or backrests 69, 69 are respectively adjustably mounted on the seat-forming end portions of the seesaw member 17 outwardly from the hand holds 61 and 64 and in co-operative relation therewith, these backrests facing towards each other and towards the respective hand holds. The backrests 69, 69 are adjustable along the seat-forming end portions of the seesaw member 17 toward and away from its fulcrum rod 18 in order to enable riders of different weight to balance each other on the seesaw member. The seatbacks 69, 69 and the

hand holds 61 and 64 being correspondingly but independently adjustable co-operate in enabling the riders to maintain their position without slipping. The two backrests 69, 69 may be of identical construction, as shown in the drawings, and formed, for the most part at least, from suitably shaped sheet metal. Each of the seat-forming end portions of the seesaw plate member 17 has provided through it along its center line, a series of apertures 70, 70 shown as five in number, which are utilized for holding the backrest in adjusted position.

The backrest 69 is shown as of substantially semi-circular shape and as rising perpendicularly from the seesaw plate member 17. This backrest has forwardly extending side arms the forward end portions of which lie outside of and clear of the edges of the seesaw member, the upper side of the seesaw member being entirely unobstructed by these forward end portions of the side arms. Each of these side arm end portions has a downward projection or lug formed thereon in the same piece therewith, the upper portion 71 of which extends straight down at the edge of the seesaw member plate 17 below which this lug is turned over to project inward, thus forming a hook end 72 which engages with, or hooks, beneath the lower side of the seesaw member 17 for holding down the backrest 69, preventing it from tilting backward while providing for it being freely tilted forward on the seesaw member. The rear edge of the hook end 72 is shown as projecting slightly to the rear edge of the vertical side portion 71 of the lug, so as better to serve as a fulcrum in the tilting or swinging movement of the backrest. The vertical lug portion 71 may slightly frictionally grip the edges of the seesaw member, so as to prevent undesirable looseness of the backrest.

The backrest 69 at its back rigidly carries a downwardly projecting stud 73 which may pass freely through any one of the apertured holes 70, 70 and for increased security of engagement projects somewhat below the lower side of the seesaw member 17, and will securely hold the backrest against slipping. By tilting the backrest 69 forwardly the stud 73 will be withdrawn from an aperture 70, permitting the backrest then to be moved slidably along the seesaw member and its stud 73 to be re-engaged in another aperture 70 by swinging the backrest rearwardly to its normal position at a different position of adjustment relatively to the fulcrum rod 18 of the seesaw member.

Besides the co-operating adjustable seat backs 69, 69 and hand holds 61 and 64, further means are provided for balancing an excess of weight on one end of the seesaw member 17, such means being shown as an adjustable spring counterbalance. In the illustrated construction, two extensible or retractile coiled counterbalance springs 74 and 75 are adjustably connected together in series relation by means of a turnbuckle 76 of substantially usual construction. One of these springs 74 is shown as longer and is also somewhat weaker or less resistant, as indicated by its extension, than the other spring 75. The free end of the longer spring 74 is shown as disconnectably anchored to the platform frame plate 1 just at the front of the gear frame 26 by means of a hook 77 which is secured by bolts 78, 78 to the upper side of the reinforcing strip 80 and to the frame plate 1. The remote or outer end of the other or shorter spring 75 is shown as disconnectably attached to the front

end of the seesaw member 17 by means of a hook 79 below the seesaw member and secured thereto by bolts 80, 80 having flat heads countersunk into the upper side of the seesaw member.

The springs 74 and 75 may be adjusted by means of the turnbuckle 76 to compensate for a heavier rider on the rear seat of the seesaw member, particularly in case, for example, the rear rider should be an adult with a small child as a front rider. Furthermore, with no front rider and in lieu thereof, the above described adjustable spring counterbalance provides for the use of the traveling seesaw device by a single rider, whose weight on the rear seat would be counterbalanced by a corresponding adjustment of the springs 74, and 75. When there is not too much difference in weight between a front rider and a rear steering rider, the upper spring 73 may be disconnected from its hook 79 on the seesaw member, or the lower spring 75 may be also disconnected and the retractile counterbalancing connection comprising the springs 74 and 75 with their turnbuckle 76 then entirely removed.

The double-pointed arcuate arrow towards the front end of the seesaw member 17 (Figure 2) indicates the complete rocking movement of this member, the front and rear outside end arrows show the next immediate direction of rocking movement of the seesaw member in the forward travel of the device with the cranks 27 and 28 positioned as shown, the forward direction of rotation of the traction wheel 3 being indicated by the arrow thereon, while the forward direction of travel of the device is indicated by the outside front straight arrow. The operation of the traveling seesaw device, to whatever extent not obvious, is believed to have been already fully described in connection with the description of its construction. It is obvious that various modifications may be made in the construction shown in the drawings and above particularly described, within the principle and scope of the invention as defined in the appended claims.

What I claim is:—

1. In a traveling seesaw device, the combination of a frame including an upright thereon, a seesaw member pivoted on the upright to extend fore and aft of the frame, supporting wheels for the frame to include a traction wheel and a steering wheel, means for driving the traction wheel from the seesaw member, an upright sectional telescopic steering shaft to which the sections are coupled together to turn as a unit irrespective of their relative telescopic movement, the lowermost section of said shaft being mounted on the frame and the uppermost section of this shaft being carried by the seesaw member to move up and down therewith at a point towards one end thereof from its pivot, steering connections between said lowermost shaft section and the steering wheel, and a steering handle fixed on the said uppermost shaft section above the seesaw member.

2. The invention defined in claim 1, in which the said steering connection includes a pair of co-operating oppositely movable flexible connecting members.

3. In a see-saw device, the combination of a seesaw member fulcrumed for rocking movement, and a backrest mounted on the seesaw member for adjustment thereon relatively to its fulcrum, an end portion of the seesaw member having a longitudinal series of holes therein substantially along its center line, the backrest at its back rigidly carrying a downwardly project-

ing stud freely removably to enter any one of said holes, the backrest having forwardly extending side arms the forward end portion of which clear the edges of the seesaw member and leave its upper side unobstructed, and downwardly projecting lugs carried by the forward end portion of the side arms to extend freely past the edges of the seesaw member and having inturned projections to engage beneath the seesaw member thereby providing for the backrest to be tilted forwardly to disengage its back stud from one of said holes in the seesaw member.

4. In a traveling seesaw device, the combination of a frame, a seesaw member fulcrumed at thereon at an elevated position, supporting wheels for the frame to include a traction wheel, a small spur gear coaxially connected to the traction wheel to drive the latter, a larger spur gear meshing with said smaller gear, a crank coaxially connected to the larger gear for rotating the latter, and a connecting rod pivotally connecting the crank to the seesaw member at a point farther removed from its fulcrum than the length of the crank, whereby the multiplying action of the said gears will correspondingly increase the speed of travel of the said device.

5. In a traveling seesaw device, the combination of a frame, a seesaw member fulcrumed at an elevated position on the frame, supporting wheels for the frame to include a traction wheel, and operating mechanism connecting the seesaw member with the traction wheel, such mechanism

including a crank shaft journaled on the frame and provided with opposed cranks, a connecting rod operatively connecting one of these cranks to the seesaw member at one side of the fulcrum of the latter, and a two-part connecting rod of which the parts are relatively telescopically freely slideable longitudinally of one another with one of its said parts pivoted on the other crank and with its other said part pivoted to the seesaw member at the other side of its fulcrum from the said operating connected connecting rod.

6. In a traveling seesaw device, the combination of a frame, a seesaw member fulcrumed at an elevated position on the frame, supporting wheels for the frame to include a traction wheel, and operating mechanism connecting the seesaw member with the traction wheel, such mechanism including a crank shaft journaled on the frame and provided with opposed cranks, a pair of longitudinally telescopic connecting rods respectively pivotally connecting the cranks to the seesaw member at respectively opposite sides of its fulcrum, and locking means for each of the connecting rods to lock it in telescopically adjusted condition while the other connecting rod is left unlocked for free telescopic movement, whereby either of the connecting rods may be utilized as an operating rod and the position of the seesaw member may be adjusted by adjustably lengthening or shortening this operating rod.
